1244, 1245, 1246, 1247, 1248, 1249, 1249, 1250, 1251, 1252, 1253, 1254, 1255, 1256, 1257, 1258, 1259, 1259, 1260, 1261, 1262, 1263, 1264, 1265, 1266, 1267, 1268, 1269, 1269, 1270, 1271, 1272, 1273, 1274, 1275, 1276, 1277, 1278, 1279, 1279, 1280, 1281, 1282, 1283, 1284, 1285, 1286, 1287, 1288, 1289, 1289, 1290, 1291, 1292, 1293, 1294, 1295, 1296, 1297, 1298, 1299, 1299, 1300, 1301, 1302, 1303, 1304, 1305, 1306, 1307, 1308, 1309, 1309, 1310, 1311, 1312, 1313, 1314, 1315, 1316, 1317, 1318, 1319, 1319, 1320, 1321, 1322, 1323, 1324, 1325, 1326, 1327, 1328, 1329, 1329, 1330, 1331, 1332, 1333, 1334, 1335, 1336, 1337, 1338, 1339, 1339, 1340, 1341, 1342, 1343, 1344, 1345, 1346, 1347, 1348, 1349, 1349, 1350, 1351, 1352, 1353, 1354, 1355, 1356, 1357, 1358, 1359, 1359, 1360, 1361, 1362, 1363, 1364, 1365, 1366, 1367, 1368, 1369, 1369, 1370, 1371, 1372, 1373, 1374, 1375, 1376, 1377, 1378, 1379, 1379, 1380, 1381, 1382, 1383, 1384, 1385, 1386, 1387, 1388, 1389, 1389, 1390, 1391, 1392, 1393, 1394, 1395, 1396, 1397, 1398, 1399, 1399, 1400, 1401, 1402, 1403, 1404, 1405, 1406, 1407, 1408, 1409, 1409, 1410, 1411, 1412, 1413, 1414, 1415, 1416, 1417, 1418, 1419, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1479, 1479, 1480, 1481, 1482, 1483, 1484, 1485, 1486, 1487, 1488, 1489, 1489, 1490, 1491, 1492, 1493, 1494, 1495, 1496, 1497, 1498, 1499, 1499, 1500, 1501, 1502, 1503, 1504, 1505, 1506, 1507, 1508, 1509, 1509, 1510, 1511, 1512, 1513, 1514, 1515, 1516, 1517, 1518, 1519, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1579, 1579, 1580, 1581, 1582, 1583, 1584, 1585, 1586, 1587, 1588, 1589, 1589, 1590, 1591, 1592, 1593, 1594, 1595, 1596, 1597, 1598, 1599, 1599, 1600, 1601, 1602, 1603, 1604, 1605, 1606, 1607, 1608, 1609, 1609, 1610, 1611, 1612, 1613, 1614, 1615, 1616, 1617, 1618, 1619, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1698, 1699, 1699, 1700, 1701, 1702, 1703, 1704, 1705, 1706, 1707, 1708, 1709, 1709, 1710, 1711, 1712, 1713, 1714, 1715, 1716, 1717, 1718, 1719, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1759, 1759, 1760, 1761, 1762, 1763, 1764, 1765, 1766, 1767, 1768, 1769, 1769, 1770, 1771, 1772, 1773, 1774, 1775, 1776, 1777, 1778, 1779, 1779, 1780, 1781, 1782, 1783, 1784, 1785, 1786, 1787, 1788, 1789, 1789, 1790, 1791, 1792, 1793, 1794, 1795, 1796, 1797, 1798, 1799, 1799, 1800, 1801, 1802, 1803, 1804, 1805, 1806, 1807, 1808, 1809, 1809, 1810, 1811, 1812, 1813, 1814, 1815, 1816, 1817, 1818, 1819, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1859, 1859, 1860, 1861, 1862, 1863, 1864, 1865, 1866, 1867, 1868, 1869, 1869, 1870, 1871, 1872, 1873, 1874, 1875, 1876, 1877, 1878, 1879, 1879, 1880, 1881, 1882, 1883, 1884, 1885, 1886, 1887, 1888, 1889, 1889, 1890, 1891, 1892, 1893, 1894, 1895, 1896, 1897, 1898, 1899, 1899, 1900, 1901, 1902, 1903, 1904, 1905, 1906, 1907, 1908, 1909, 1909, 1910, 1911, 1912, 1913, 1914, 1915, 1916, 1917, 1918, 1919, 1919, 1920, 1921, 1922, 1923, 1924, 1925, 1926, 1927, 1928, 1929, 1929, 1930, 1931, 1932, 1933, 1934, 1935, 1936, 1937, 1938, 1939, 1939, 1940, 1941, 1942, 1943, 1944, 1945, 1946, 1947, 1948, 1949, 1949, 1950, 1951, 1952, 1953, 1954, 1955, 1956, 1957, 1958, 1959, 1959, 1960, 1961, 1962, 1963, 1964, 1965, 1966, 1967, 1968, 1969, 1969, 1970, 1971, 1972, 1973, 1974, 1975, 1976, 1977, 1978, 1979, 1979, 1980, 1981, 1982, 1983, 1984, 1985, 1986, 1987, 1988, 1989, 1989, 1990, 1991, 1992, 1993, 1994, 1995, 1996, 1997, 1998, 1999, 1999, 2000, 2001, 2002, 2003, 2004, 2005, 2006, 2007, 2008, 2009, 2009, 2010, 2011, 2012, 2013, 2014, 2015, 2016, 2017, 2018, 2019, 2019, 2020, 2021, 2022, 2023, Specification of Letters Patent.

Patented Apr. 23, 1912.

Application filed January 10, 1910. Serial No. 537,345.

To all whom it may concern:

Be it known that we, JOHN STAFFORD, a subject of the King of Great Britain, and OTIS C. CURRIE, a citizen of the United States, both residing at Detroit, county of Wayne, State of Michigan, have invented a certain new and useful Improvement in Multiple Type-Writer Presses, and declare the following to be a full, clear, and exact description of the same, such as will enable others skilled in the art to which it pertains to make and use the same, reference being had to the accompanying drawings, which form a part of this specification.

This invention relates to multiple type-writer presses and its object is a device in which type set up in a flat bed or tray may be used to produce a result identical in appearance with that produced in a typewriting machine.

It is also an object of the invention to provide means whereby the ribbon, through which the impression is made, moves automatically across the face of the type both longitudinally and cross-wise thereof, thereby maintaining uniformity of color throughout the entire ribbon.

Other objects and novelties of the invention, such as the means for registering whereby the printing occupies the same relative position on all printed sheets and the means for feeding the blank sheets on to the type bed, etc., are hereinafter more fully described and claimed.

In the drawings—Figure 1 is a side elevation of a machine embodying our invention. Fig. 2 is a longitudinal section thereof. Fig. 3 is a section on line $x-x$ of Fig. 2. Fig. 4 is a detail of the ribbon actuator. Fig. 5 is a plan view showing the means for producing a crosswise movement of the ribbon during its longitudinal movement across the face of the type. Fig. 6 is a detail of the means for clutching the ribbon spool to its shaft. Fig. 7 is a longitudinal section of Fig. 6. Fig. 8 is a detail of the means for operating the ribbon actuator. Fig. 9 is a detail of the means for releasing the pawl which operates the mechanism for producing the crosswise movement of the ribbon. Fig. 10 is a detail of the stop operating means. Fig. 11 is a detail of the clutch for operating the platen to feed the paper on to the type bed. Fig. 12 is a perspective view

showing the catch for releasing the lever 55 that reciprocates the platen. Fig. 13 is a plan view of the jaw that removes the printed sheet from the type bed. Fig. 14 is a cross sectional view of the platen and the feed roll showing, in dotted lines, the position assumed by the parts when feeding paper on to the type bed.

Similar letters refer to similar parts throughout the drawings and specification.

A, A' indicate the side frames which are 65 supported by the cross bars a , a' , etc., in ways w in which side frames the type bed B is reciprocatingly mounted. The type bed, as shown in Figs. 2 and 3, is adapted to carry a tray g in which the type t are set up. 70 The reciprocation of the bed is accomplished by means of the connecting rod r , one end of which is attached to the cam wheel C^2 on the main shaft C, the opposite end being pivotally attached to a lever L which is 75 keyed to the shaft a' mounted in bearings in the frames A, A'. The lever L' is also keyed to the shaft a' and to the free ends of the levers L and L' are pivotally attached the connecting rods or bars b and b' , the 80 opposite ends of which are attached to lugs on the bed B. The rotation of the shaft C and cam wheel C^2 consequently reciprocates the bed. Spools S and S' are mounted on shafts r' at each end of the bed B and are 85 adapted to carry the ribbon R across the face of the type as hereinafter more fully described. As shown in Figs. 1 and 2, a platen P is reciprocatingly mounted above the type bed B. The type bed reciprocates 90 in a horizontal plane and the platen reciprocates in a vertical plane and during the forward movement of the bed the platen is held in contact therewith and during the return movement of the bed is held out of 95 contact therewith. The platen is also rotatable on the shaft P' by means of the rack d, on the bed B, and the gear G loosely mounted on the collar Q² attached to the platen. The teeth of the gear are of such 100 length that they are never out of mesh with the rack during the reciprocating movement of the platen. Therefore, in order that the rack may not rotate the platen during the return movement of the bed, the gear G is 105 not directly connected to the platen but is provided with a clutch whereby said gear rotates the platen during the forward move-

ment of the bed and does not rotate the platen during the return movement of the bed, although the gear itself does rotate.

The shaft P' , on which the platen is mounted, is supported by the hangers h and h' , one on each side of the machine, in a recess in the frames provided therefor. The lower end of each hanger h and h' is pivotally connected to levers i and i' respectively, which are pivoted on the side frames at j and j' . Also pivoted at j and j' are the levers k and k' carrying the cam rollers m and m' which ride on the cam wheels C' and C^2 . Both the levers i and k have upwardly extending ends i^2 and k^2 and a thumb screw n is threaded in the end k^2 of the lever k and bears against the dog d^4 pivoted on the end i^2 of the lever i . The levers i' and k' are also provided with upwardly extending ends and attached parts and have the same design and function as the levers i and k , consequently the description of one set of levers will do for both. The dog d^4 has a thumb piece d^5 by means of which it may be withdrawn from between the end of the thumb screw and the end i^2 of the lever i as shown in dotted lines in Fig. 12. The cam roller m on the lever k rides on the cam C' , as heretofore stated, and, by means of the thumb screw n , lever i , and the hanger h , intermittently brings the platen into contact with the type bed. The levers i' and k' are actuated at the same time as the levers i and k , but are connected to the opposite end of the platen shaft, by reason of which the platen has an equal pressure on the type bed throughout its length. If for any reason it is desired to operate the machine without reciprocating the platen, the dog d^4 on the upwardly extending part of the levers i and i' is raised out of the path of movement of the thumb screws n , allowing the levers k and k' to move freely on their pivots j and j' . The adjusting screw n provides a means whereby the looseness of the joints and the spring of the levers may be taken up and the platen held firmly when in contact with the bed.

In order to prevent the platen from being forced down between the lines of type by the pressure produced by the above described mechanism, and also to accurately gage the ink impression resulting therefrom, stops s , s , are provided against which the platen shaft P' rests when in the printing position. Brackets B' are bolted to each frame below the end of the shaft P' and are provided with a recess in which the hangers h and h' reciprocate. The stops s , which are simply cap screws, are located in tapped holes s^2 in the brackets and cap screws s' are inserted in the holes from the lower side forming a lock for the screws s . By adjusting the lock screws s' and the stops s and thumb screws n heretofore men-

tioned, a greater or less pressure is produced between the platen and the bed. Springs s^3 are mounted on the brackets and are adapted to hold the platen out of contact with the bed.

A feed roller F is mounted above the platen in slots h^{10} in the hangers h and h' and a feed table T is attached to a cross bar of the frame in a proper position for the insertion of blank sheets of paper between the feed roller and the platen. The feed roller has a reciprocating motion in the slots in the hangers toward and away from the platen, which is accomplished by mechanism hereinafter described, and during the time the roller is lifted away from the platen the paper is inserted therebetween and rests against the paper stops S^2 , S^2 and as the feed roller F is brought into contact with the paper, the stops S^2 are lifted out of the path of movement thereof allowing the paper to be fed forward due to the rotation of the platen and the roller. A shield H is supported on the roller F by the hangers h^{11} and rests against the platen as shown in Figs. 2 and 14 and a slight tension between the shield and the platen is produced by the spring s^4 attached to the hollow cross bar b^5 as shown. The shield provides a means for properly placing the paper on the type bed and the stops S^2 provide a means of registering whereby the printing occupies the same position on all the printed sheets, the utility of which is in facilitating the insertion of names and dates, etc., by means of a typewriter, on such matter as circular letters. The feed roller is raised from contact with the platen by the rock arm a^5 and connecting bar a^6 attached to the cam lever c^6 , which is actuated by the cam C^3 . The cam lever c^6 is provided with a roller r^3 against which the cam rides. The rock arm a^5 is attached to the rock shaft a^7 passing through the hollow cross bar b^5 and, on the opposite end, the shaft a^7 is provided with a rock arm a^8 . The rock arms a^5 and a^8 are positioned below the projecting ends of the feed roller F as shown in Fig. 3, thus providing means at each end of the feed roller for lifting it out of contact with the platen. The stops S^2 are actuated by the cam lever c^6 by means of the connecting bar a^9 , rock arm a^{10} , and rock shaft a^{12} . The connecting bar a^9 is slotted at the end to which the cam lever c^6 is attached, as said lever has a greater movement than is necessary to operate the stops, and, as is shown in Fig. 10, a spring s^6 is mounted on the shaft a^{12} which tends to hold the stop S^2 in position to stop the paper when inserted between the feed roller and the platen, and the cam lever only serves to raise the stops out of contact with the platen and allow the paper to be fed on to the bed. The spring s^7 , which is attached

to the rock arm a^5 and the frame A, returns the cam lever to its normal position after being acted upon by the cam C^3 , and during the latter part of the movement of 5 the cam lever c^6 , caused by the action of the spring s^7 , the stops are raised out of contact with the platen by the slotted connecting bar a^9 . When the cam lever c^6 is raised by the cam C^3 , the feed roller F is raised 10 out of contact with the platen by the rock arms a^5 and a^8 as heretofore described and the stops S^2 are brought into contact with the platen by the spring s^6 on the shaft a^2 shown in Fig. 10. In its normal position as 15 shown in Fig. 1, the cam lever c^6 holds the stops S^2 out of contact with the platen as the spring s^7 is of sufficient strength to overcome the action of the spring s^6 which tends to hold the stops S^2 in contact with the 20 platen. The utility of the slot in the bar a^9 is not only in allowing the lever c^6 to move upward without interfering with the described action of the stops S^2 , but, on the return movement, allows the feed roller F to 25 come in contact with the impression sheet (which has been inserted while the roller was raised) before the end of the lever c^6 strikes the end of the slot and lifts the stops out of contact with the platen. If the movement 30 of the feed roller F and the stops S^2 were simultaneous, the sheet might become displaced before the roller was in place, but, by the arrangement above described, the stops remain in position until the roller 35 comes in contact with the sheet thereby preventing a displacement of the sheet. The feed roller F is grooved at f , f' , to allow the stops S^2 to be properly positioned in relation to the platen.

40 It is evident that the paper must be inserted between the platen and the type bed prior to what may be termed the printing movement thereof and also before the platen is in contact with the bed. To accomplish this 45 result, a ball clutch Q is provided at one end of the platen, loosely mounted on a collar q attached to the platen, as shown in Figs. 3 and 11. The balls q' rest in pockets q^2 in the member Q, the outer walls of which 50 are eccentric to the shaft P' and collar q . If the member Q be rotated in the direction of the arrow shown in Fig. 11, the balls q' bind between the eccentric walls and the collar and therefore rotate the platen. The 55 gear G, on the opposite end of the shaft, is provided with a clutch similar to the one above described. The clutch Q is provided with a metal tape q^8 on its periphery which is connected to a lever q^4 pivoted on the 60 frame A. The lever q^4 is connected to the cam lever Q' by the connecting bar q^5 and the cam lever is actuated by the roller r^6 on the balance wheel W' which roller r^6 contacts the cam face Q^3 of the lever Q' once 65 every revolution of the shaft C. The roller

and balance wheel are shown in dotted lines in Fig. 1 and in full lines in Fig. 3. The roller is so placed on the balance wheel that the cam lever Q' is actuated and the platen rotated prior to the finish of the return stroke of the reciprocating bed and thus places the paper in the proper printing position before the platen is in contact with the bed. The member Q is provided with a coiled spring q^6 that is placed under tension 70 when the platen is rotated by the tape and returns said member Q, lever q^4 , and cam lever Q' to their normal position after being acted upon by the cam roller r^6 . One end of the spring is attached to the member Q and the opposite end is attached to the frame A. The spring is shown in section in Fig. 3.

The cams C' and C^2 that bring the platen into contact with the type bed are timed to produce said contact slightly prior to the forward or printing stroke of the bed B. The platen is then rotated by the rack d and the gear G in the same direction as is produced by the clutch Q. The clutch Q rotates the platen, which with the coacting 85 parts brings the end of the impression sheet to the printing position between the platen and the bed prior to the contact of the platen with the bed, and the rack d and gear G rotate the platen during the printing movement of the bed. The platen is in contact with the bed during said printing movement and the coaction therebetween continues the feeding of the impression sheet on to the bed. At the finish of the printing stroke of 90 the bed, the printed sheet is grasped by the jaws J and J' and, as the bed retreats, the paper falls into the pan or receiver U provided for such purpose. The jaw J is operated by rock shaft j^6 , rock arm j^7 , connecting rod j^8 , bell crank j^9 , and rod j^{10} attached to the lever k as shown in Fig. 1. It will thus be seen that, as the bed completes the forward stroke and the lever k releases the platen from contact with the bed and the paper thereon, the jaw grasps the paper, as shown in Fig. 2, and as the bed retreats the paper naturally falls into the receiver U 95 shown in dotted lines in Fig. 2.

As heretofore stated, the ribbon has a 100 movement both longitudinal and crosswise of the bed, the utility of which is in maintaining uniformity of color in the ribbon. It is evident that forms set up in the tray may not all be of uniform width and, if no 105 provision was made for a crosswise movement of the ribbon, the central part thereof would become worn with those forms that were narrow and, when a wider form was 110 used the resulting impression would be much heavier on the edges than in the central part. With a gradual shifting of the ribbon crosswise of the bed, this defect is eliminated as the ribbon is equally used throughout its 115 width. The ribbon movement is produced 120

by the pawls e , e' , and e^2 acting on the ratchets e^3 , e^4 , and e^5 . The pawls are attached to the reciprocating bar E and are spring controlled as shown in Fig. 4. The 5 ratchets e^3 and e^5 are mounted on the shafts r' one at each end of the type bed B and the ratchet e^4 is mounted on the shaft e^6 near the center of the bed. The shafts r' carry the ribbon spools S , S' and have a keyway 10 w^2 , shown in Figs. 5 and 7, in which the pin w^3 engages when the spool is locked to the shaft. The pin is retained in position by the spring w^4 attached to the end of the spool and said pin is bent as shown, and 15 when the horizontal part is parallel with the shaft, it will drop into the notch w^5 on the end piece of the spool and the lower end will enter the keyway w^2 and consequently lock the spool to the shaft. The 20 keyway w^2 is of sufficient length to allow the spool to be moved longitudinally on the shaft. To release the spool from the shaft, the pin w^3 is raised out of the notch w^5 and the bent end turned at right angles to 25 the axis of the shaft. The lower end is then out of the keyway and the shaft is free to revolve without rotating the spool. The spring w^4 retains the pin in either position in which it may be placed. An examination 30 of Fig. 4 will show that a reciprocation of the bar E rotates both shafts r' on which the spools S are mounted, consequently one of the spools must be free from the shaft in order that the ribbon may have a movement 35 longitudinal of the bed B . To reverse the movement of the ribbon, the free spool is locked to its shaft and the opposite one released from its shaft.

The bar E is carried by the reciprocating 40 bed B and, as is shown in Figs. 4 and 8, the actuating bar X is moved longitudinally of the bed, and, by means of the bent and notched end acting against the pin x' in the bar E , moves said bar E longitudinally of 45 the bed. This movement of the bar places the spring x^6 under tension which returns the parts to their normal position when released by the forward movement of the bed. The bar X is held on the bed by the screw 50 x^2 in the slot x^3 , and the bar X is also provided with a pin x^4 which, as the bed approaches the finish of the return stroke, strikes against the lug x^5 on the frame and as the bed continues its movement the bar X 55 slides longitudinally of the bed and actuates the bar E as above described.

The movement of the ribbon crosswise of the bed is caused by the pawl e' which intermittently rotates the ratchet e^4 and shaft e^6 . 60 A barrel cam e^7 is mounted on the shaft e^6 and in the cam groove e^8 a pin y rides. The pin y is fastened in the lever Y as shown and the lever Y' is provided with a forked end y^2 adapted to encircle the end of the lever Y 65 in which the pin is located. The levers Y

and Y' are otherwise essentially alike. The levers are attached to the type bed B at y^3 and y^4 as shown in Fig. 2 and have forked ends y^5 and y^6 that are adapted to ride in a groove z on the spools as shown in Fig. 5. 70 It is therefore evident that a rotation of the barrel cam e^7 will move the spools S , S' longitudinally on their shafts r' , thereby producing a movement of the ribbon crosswise of the type bed. If the type form set up in the tray is as wide as the ribbon, it becomes unnecessary for the ribbon to have a movement crosswise of the bed and to stop said movement of the ribbon, the pawl e' is raised out of engagement with the ratchet e^4 by means of a latch Z attached to the bed as shown in Fig. 4. A bottom view of the latch is also shown in Fig. 9. The latch is provided with a slot z' in which is the screw z^2 holding it in position on the bed. 75 A bent end z^3 of the latch is adapted to lift the pawl e' out of engagement with the ratchet e^4 when said latch is moved longitudinally of the bed. A bent end z^4 provides a means whereby the latch may be 80 moved and the screw z^2 holds the latch in whatever position it may be placed. 85

In operation, the feed roller F is raised out of contact with the platen and the stops S^2 brought into contact therewith prior to 90 the printing movement of the bed B . During this interval the blank paper is inserted between the feed roller and the platen and rests against the stops S^2 . As the feed roller is again brought into contact with the platen, the stops are raised out of contact therewith and the cam lever Q' is actuated which, in turn, actuates the clutch Q . The clutch Q rotates the platen and feed roller and feeds the paper forward during the latter part of the return movement of the bed. The shield H guides the paper on to the bed between the platen and the bed, the platen being out of contact with the bed during 100 the entire backward or return movement thereof. At the finish of the return stroke, the ribbon is moved forward by the slide bar X and coating mechanism heretofore described. As the type bed is about to start on its forward or printing stroke, the cams C' , C^2 bring the platen into printing contact with the bed by means of the cam rollers m , m' and connected levers. During this forward stroke of the bed the platen is rotated by means of the rack and gear heretofore described in detail. The rotation of the platen continues to feed the paper on to the bed and, as the bed reaches the limit of its forward movement, the platen is released from its contact with the bed and the jaws J and J' grasp the printed sheet of paper by reason of the cam rollers dropping on to the lower part of the cams C' and C^2 . The springs S^3 hold the cam rollers in contact 110 with the cams. The jaw J' is stationary, 115

being mounted on the inner ends of the tubes T^2 , T^3 as shown in Fig. 13. The tubes are mounted in brackets b^{15} on the side frames, as shown in Figs. 1 and 13. The jaw J is 5 mounted on the rock shaft j^6 which is located in the tubes as shown. As the bed begins its return movement, it retreats from under the paper, allowing it to drop into the receiver U when released by the jaw at 10 the finish of the stroke.

Having thus briefly described our invention, what we claim is—

1. In a multiple typewriter press, a reciprocating, type carrying bed, an ink ribbon carried thereby, means for automatically moving the ribbon over the face of the type, a platen mounted in the framework that supports the bed, said platen being positively rotated during the printing movement of 15 the bed, a clutch adapted to rotate the platen prior to the completion of the return movement of the bed, means coacting with the platen during its rotation by the clutch adapted to place an end of an impression 20 sheet between the platen and the bed, and means for producing pressure between the platen and the bed during the printing movement of the bed, substantially as shown and described.
2. In a multiple typewriter press having a suitable framework and operating means, of a reciprocating bed mounted in the framework, a type tray carried by the bed, a platen mounted in the framework and 25 adapted to feed paper on to the type bed during the printing movement thereof, means for rotating the platen prior to the printing movement of the bed, means coacting with the platen to feed paper to the 30 printing position prior to said printing movement of the bed, an ink ribbon carried by the bed, and means for producing pressure between the platen and the bed, substantially as shown and described.
3. In a multiple typewriter press, a reciprocating bed mounted in a framework and adapted to hold the printing form, an impression ribbon carried by the bed, a platen reciprocatingly mounted in the framework, 35 means for reciprocating the platen whereby pressure is intermittently produced between the printing surface and the platen, means on the platen whereby it may be rotated prior to the printing movement of the bed, 40 means coacting with the platen whereby said rotation feeds paper into printing position, and means for moving the ribbon over the printing form, substantially as shown and described.
4. In a multiple typewriter press, a framework, a reciprocating bed mounted in ways therein, a tray adapted to hold the printing form, said bed being adapted to receive said tray, an ink ribbon carried by the bed 45 and arranged to be intermittently moved

across the printing surface, a platen mounted in the framework, a feed roller held in coöperative relation with the platen, means for intermittently producing pressure between the platen and the printing surface, 70 means for rotating the platen and feed roller prior to the printing movement of the bed thereby causing the impression sheet to be fed to printing position, and means for rotating the platen during the printing movement of the bed thereby feeding the impression sheet on to the type form, substantially as shown.

5. In a multiple typewriter press, a framework, a reciprocating bed mounted therein, 80 a tray adapted to hold the printing form, said bed being adapted to receive said tray, an ink ribbon carried by the bed and arranged to be intermittently moved across the printing surface both longitudinally and 85 transversely thereof, a platen mounted in the framework, a feed roller held in coöperative relation with the platen, means for intermittently producing pressure between the platen and the printing surface, means 90 for rotating the platen and feed roller prior to the printing movement of the bed thereby causing the impression sheet to be fed to printing position, and means for rotating the platen during the printing movement of 95 the bed thereby feeding the impression sheet on to the printing form, substantially as shown and described.

6. In a multiple typewriter press, a reciprocating, type carrying bed, an ink or impression ribbon carried on spools mounted on the bed, means comprising a spring controlled reciprocating bar carried by the bed and having a pawl for rotating the spools thereby moving the ribbon across the printing surface, means comprising pivoted levers carried by the bed and controlled by the reciprocating bar for producing an end-wise movement of the spools simultaneously 100 with the rotating movement whereby uniformity of color in the ribbon is maintained, a platen mounted in the framework that supports the bed, the platen being adapted to feed paper on to the type bed, and means for intermittently producing a pressure between the platen and the type bed, substantially 105 as shown and described.

7. In a multiple typewriter press, a reciprocating bed mounted in a framework and adapted to hold the printing form, an 110 ink ribbon carried by the bed and covering the printing form, a platen mounted in hangers in the framework, said hangers having a reciprocating movement whereby pressure is intermittently produced between the 115 platen and the printing form, means for rotating the platen prior to the printing movement of the bed, means coacting with said platen whereby said rotation thereof is adapted to feed the impression sheet 120 125 130

into printing position, the engagement of the impression sheet between the platen and the printing form providing a means for feeding the impression sheet on to the printing form during the printing movement of the bed, and means for removing the printed sheet from the bed, substantially as shown and described.

8. In a multiple typewriter press, a reciprocating bed mounted in a framework and adapted to hold the printing form, an ink ribbon carried by the bed and covering the printing form, a platen mounted in hangers in the framework, said hangers having a reciprocating movement whereby pressure is intermittently produced between the platen and the printing form, means for rotating the platen prior to the printing movement of the bed, a roller carried by the hangers and coacting with the platen whereby said rotation of the platen is adapted to feed the impression sheet into printing position, the engagement of the impression sheet between the platen and the printing form providing a means whereby the printing movement of the bed causes the impression sheet to be fed on to the printing form substantially as shown and described.

9. A multiple typewriter press comprising a framework, a reciprocating bed mounted in ways therein, a tray adapted to hold the printing form, said bed being adapted to receive said tray, an ink ribbon carried by the bed and arranged to be intermittently moved across the printing form, a platen mounted in the framework, means for intermittently bringing the platen into contact with the printing form, a clutch mounted on the platen shaft adapted to rotate the platen prior to the printing movement of the bed, means coacting with the platen when out of contact with the printing form to feed the impression sheet to printing position, and stops limiting the distance that the sheet may be inserted into the feeding device prior to said rotation of the platen by the clutch, substantially as shown and described.

10. A multiple typewriter press comprising a framework, a reciprocating bed mounted in ways therein, a rack on said bed, a tray adapted to hold the printing form, said bed being adapted to receive said tray, an ink ribbon carried by the bed and arranged to be intermittently moved across the printing form, a platen mounted in the framework, means for intermittently bringing the platen into contact with the printing form, a clutch at one end of the platen adapted to rotate the platen prior to the printing movement of the bed, means whereby said rotation of the platen causes the impression sheet to be fed to printing position, a clutch on the opposite end of the platen having a gear on its periphery mesh-

ing with the rack on the bed whereby the platen is rotated during its contact with the printing form, and means for removing the printed sheet from the form, substantially as shown.

11. In a multiple typewriter press, a reciprocating, type carrying bed, an ink ribbon carried thereby, means for intermittently moving the ribbon over the face of the type, a platen mounted in the framework that supports the bed, means for rotating the platen prior to the printing movement of the bed, means coacting with the platen during said rotation to feed the impression sheet to printing position, means for intermittently producing pressure between the platen and the bed, and means limiting said pressure, substantially as shown and described.

12. In a multiple typewriter press, a reciprocating, type carrying bed, an ink ribbon carried thereby, means for intermittently moving the ribbon over the face of the type both longitudinally and crosswise thereof, means for reversing the longitudinal movement of the ribbon, a platen mounted in the framework that supports the bed, means coöperating with the platen to feed paper on to the type bed, means for intermittently producing a pressure between the platen and the bed, and adjustable stops limiting said pressure, substantially as shown and described.

13. A multiple typewriter press comprising a reciprocating, type carrying bed, an impression ribbon carried on spools mounted on shafts carried by the bed, means on the spools whereby they may be locked to the shaft, means for rotating the shafts thereby moving the ribbon longitudinally over the type bed, said means comprising ratchets on said shafts actuated by pawls carried by a reciprocating bar mounted on the bed, means for producing an endwise movement of the spools on their shafts comprising a shaft and ratchet actuated by a pawl carried by the reciprocating bar, a cam on the shaft, levers pivoted on the bed, said levers being oscillated by the cam, one end of each lever being connected to a spool whereby their oscillation moves each spool endwise on its shaft and thereby produces a movement of the ribbon crosswise of the type bed simultaneously with its movement longitudinally thereof, a platen mounted in the framework that supports the bed, means coöperating with the platen to feed paper on to the type bed, and means for intermittently producing a pressure between the platen and the type bed, substantially as shown and described.

14. A multiple typewriter press comprising a framework, a reciprocating, type carrying bed mounted in ways therein, an impression ribbon carried on spools mounted on shafts carried by the bed, a spring re-

tained pin carried on each of the spools whereby they may be locked to their respective shafts, means for rotating the shafts thereby moving the ribbon longitudinally across the printing surface, means for producing an endwise movement of the spools on their shafts thereby moving the ribbon crosswise of the bed, a platen mounted in the framework, means coöoperating with the platen to feed paper on to the type bed, and means for intermittently producing a pressure between the platen and the type bed, substantially as shown and described.

15. In a multiple typewriter press, a reciprocating bed mounted in a framework and adapted to hold the printing form, an ink ribbon carried by the bed and covering the printing form, a platen mounted in hangers in the framework, said hangers having a reciprocating movement whereby pressure is produced between the platen and the printing form during the printing movement of the bed, a roller carried by the hangers and coacting with the platen to feed the impression sheet into printing position during the return movement of the bed, said roller having a reciprocating movement independent of the reciprocating movement of the hangers whereby an impression sheet 25 may be inserted between the roller and the platen, and the engagement of the impression sheet between the platen and the printing form providing a means whereby the printing movement of the bed causes the impression sheet to be fed on to the said form.

30 16. In a multiple typewriter press, a reciprocating bed mounted in a framework and adapted to hold the printing form, an ink ribbon carried by the bed and covering the printing form, a platen mounted in hangers in the framework, said hangers having a reciprocating movement whereby pressure is produced between the platen and the 35 printing form during the printing movement of the bed, a roller carried by the hangers and coacting with the platen to feed the impression sheet into printing position during the return movement of the bed, said 40 roller having a reciprocating movement independent of the reciprocating movement of the hangers whereby an impression sheet may be inserted between the roller and the platen, stops arranged to be brought into 45 contact with the platen during the time the roller is out of contact therewith thereby limiting the distance the impression sheet 50 may be inserted between the roller and the platen, the engagement of the impression sheet between the platen and the printing form constituting a means whereby the printing movement of the bed causes the impression sheet to be fed on to the printing form.

55 17. In a multiple typewriter press, a re-

ciprocating type-carrying bed mounted in a framework, an ink ribbon carried by the bed and covering the printing surface, a platen mounted in hangers carried by the framework, means for reciprocating the hangers whereby pressure may be produced between the platen and the bed during the printing movement thereof, a roller carried by the hangers, stops carried by the framework, a spring tending to hold the stops in contact with the platen, a cam actuated lever adapted to reciprocate the roller in the hangers and subsequently raise the stops out of contact with the platen, said roller providing a means for introducing an end of an impression sheet between the platen and the bed, the engagement of the sheet therebetween constituting a means for feeding the sheet onto the bed, and means for removing the printed sheet from the bed.

60 18. In a multiple typewriter press, a reciprocating bed mounted in a framework and adapted to hold the printing form, an ink ribbon carried by the bed and arranged to be intermittently moved across the printing form both longitudinally and transversely thereof, a platen mounted in hangers in the framework, said hangers having a reciprocating movement whereby pressure is intermittently produced between the platen and the printing form, a roller carried by the hangers and coacting with the platen to feed the impression sheet into printing position, said roller having a reciprocating movement independent of the reciprocating movement of the hangers thereby lifting the roller out of contact with the platen and allowing an impression sheet to be inserted between the roller and the platen, said coaction of the roller and the platen being prior to the printing movement of the bed, stops arranged to be brought into contact with the platen during the time the roller is out of contact therewith thereby limiting the distance that the impression sheet may be inserted between the roller and the platen, and means whereby the printing movement of the bed causes the impression sheet to be fed on to the printing form, substantially as shown and described.

65 19. A multiple typewriter press comprising a framework, a reciprocating bed mounted therein, a rack on said bed, a tray adapted to hold the printing form, said bed being adapted to receive said tray, an ink ribbon carried by the bed and arranged to be intermittently moved across the printing form, means for so moving the ribbon, a platen reciprocatingly mounted in the framework, a feed roller held in coöoperative relation with the platen, means for reciprocating the platen thereby intermittently bringing the platen into contact with the printing form, a clutch at one end of the platen adapted to

rotate the platen, means for operating the clutch and rotating the platen and feed roller prior to the printing movement of the bed thereby causing the impression sheet to 5 be fed into printing position, a spring adapted to return the clutch and coacting parts to inoperative position, a clutch on the opposite end of the platen having a gear on its periphery meshing with the rack on the 10 bed whereby the platen may be rotated during its contact with the printing form and thereby feed the impression sheet on to the printing form, and means for removing the printed sheet from the form, substantially 15 as shown and described.

20. A multiple typewriter press comprising a reciprocating, type carrying bed, an impression ribbon carried on spools mounted on shafts carried by the bed, means on the spools whereby they may be locked to the shaft, means for rotating the shafts thereby moving the ribbon longitudinally over the type bed, said means comprising ratchets on said shafts actuated by pawls 25 carried by a reciprocating bar mounted on the bed, means for reciprocating said bar, means for producing an endwise movement of the spools on their shafts comprising a

shaft and ratchet actuated by a pawl on the reciprocating bar, a cam on the shaft, levers pivoted on the bed, said levers being oscillated by the cam, one end of each lever being connected to a spool whereby said oscillation moves each spool endwise on its shaft and thereby produces a movement of 30 the ribbon transversely of the type bed simultaneously with its movement longitudinally thereof, a platen reciprocatingly mounted in the framework whereby pressure is intermittently produced between the 35 platen and the type bed, means on the platen whereby it may be rotated, means coacting with the platen whereby said rotation feeds the impression sheet to printing position, and means whereby the printing movement 40 causes the impression sheet to be fed onto the bed, substantially as shown and described.

In testimony whereof, we sign this specification in the presence of two witnesses. 50
